UNITED STATES PATENT OFFICE.

WILLIAM W. GREEN, OF CHICAGO, ILLINOIS.

DUMPING-CAR.

SPECIFICATION forming part of Letters Patent No. 425,607, dated April 15, 1890.

Application filed October 9, 1888. Serial No. 287,652. (No model.)

To all whom it may concern:

Be it known that I, WILLIAM W. GREEN, of Chicago, county of Cook, and State of Illinois, have invented certain new and useful Improvements in Dumping-Cars, of which the following is a full, clear, and exact description, that will enable others to make and use the same, reference being had to the accompanying drawings, forming a part of this specification.

The object of this invention is to secure the car-body to the bed-frame in such a manner as to readily permit of the body or divisions thereof being tilted and the load discharged on either side, as will be hereinafter set forth.

Figure 1 is a side elevation of a car structure embodying my improved features; Fig. 2, a transverse section in plane 2, Fig. 1; Fig. 3, a broken-away detail of one of the standards supporting the windlass-shafts; and Fig. 4, a sectional detail in plane 4, Fig. 3.

In the drawings, A represents the framing-timbers forming the car-bed. The body of the car consists of the three separate and independent compartments or boxes B B' B², provided at each end with hinged end-gates B³ B⁴. These end-gates may be locked in place by means of the ordinary slide-bolt a, arranged vertically. The locking device consisting of the vertical bolt a', having the inner ends of the horizontal companion bolts a² a³ pivoted thereto and the outer ends engaging with the sides of the box-compartment, is preferred, as it more firmly secures the end-gate in position, and is thrown into and out of a locking engagement by the vertical movement of the principal bolt a'.

The box compartment or compartments forming the car-body may be tilted so as to discharge the load from either side of the car, as may be required, by means of the mechanism that will now be described.

The car-body or each box-compartment thereof is hinged to the bed-frame at each side by the transverse lever-hinges C C'. The alternate ends of these companion levers are attached to the under side of the car-body by the pivot-bolts a³ a⁴, (see Fig. 2,) while the opposite alternate ends are pivoted to the lugs a⁵ a⁶ by the bolts a⁷ a⁸, the lugs being rigidly bolted to the frame-timbers of the car-structure. It will be understood that this system

of lever-hinges is used in duplicate on both sides of the box-compartments. This arrangement and manner of attaching the car-body permits of the box-compartments being tilted from either side of the car, as shown in Fig. 2.

D represents a number of standards, (two being required for each box-compartment,) the lower ends of which are properly secured to the car-frame, the upper ends terminating at some distance above the car-body, and supports the windlass mechanism employed in tilting the body when discharging the load.

The upper ends of the standards D are provided with the horizontal rectangular slots b, (see Figs. 2 and 3,) in which are placed the adjustable boxes b', forming journal-bearings for the respective ends of the windlass shaft or shafts D'. Each of these shafts has winding-drums D² D³ mounted thereon. The upper ends of the windlass cables or chains D⁴ are properly secured to the winding-drums, the opposite hook ends b² detachably engaging with the lugs b³ b⁴, rigidly secured to each side and near the respective ends of the box-compartments, the hook ends of cable being shifted from the lugs at one end to the companion lugs at the other end, in accordance with the side of the car it is intended to discharge the load from, the windlass-shafts having a corresponding movement in the rectangular slots b, so as to bring the winding-drums into proper position and angle relative to the ends of the box-compartments to insure a more direct lift.

The windlass-shafts have each a worm gear-wheel d mounted thereon. The worm-shaft d' is provided with bearings d² on the upper ends of the standards D and engage with said gear-wheels. The worm-shafts have square ends to receive the hand-crank d³, by which means the motion necessary to tilt the car-body is transmitted. By this arrangement the load may be discharged from either side of the car with the same facility. The nature and simplicity of the improvement are such that a special car structure is not required, but may be used on the ordinary platform-car.

The object of dividing the car-body up into a number of compartments is to permit of the load being easily dumped by hand. Where it is intended to employ power the car-body could be tilted as a whole with the same facil-

ity. It is also obvious that the improvement could be so arranged as to discharge the load from the end of the car instead of the sides, as illustrated.

5 Having thus described my invention, what I claim, and desire to secure by Letters Patent, is—

1. In a dumping-car, the combination, with the end gate or gates of a car-body, of a locking device consisting, essentially, of a vertically-arranged bolt and two horizontal companion bolts pivoted at their inner ends to the vertical bolt, the outer ends engaging with the sides of the box-compartment, substantially as set forth.

2. In a dumping-car, the combination, with the car frame or bed and the car-body, of companion lever-hinges having alternate ends pivoted to the car frame and body, respectively, whereby the car-body may be tilted to discharge the load on either side, as may be required, substantially as and for the purpose set forth.

3. In a dumping-car, the combination, with the frame-timbers and the car-body divided into two or more compartments, of the crossed lever-hinges C C', the pivot-bolts a^3 a^4 , the lugs a^5 a^6 , secured to the frame-timbers, and the pivot-bolts a^7 a^8 , substantially as and for the purpose set forth.

4. In a dumping-car, the combination, with the car-body secured to the bed-frame by cross-hinges, as described, of the standard or stand-

ards D, provided with the rectangular slots b, the windlass-shaft adjustably journaled in 35 said standards and having winding-drums mounted thereon, and a cable or chain adjustably connecting said car-body or box-compartments, substantially as and for the purpose set forth.

5. In a dumping-car, the combination, with the car-body hinged to the bed-frame, as described, of the standards D, having slots b, the boxes b', adjustable in said slots, the windlass-shaft D', journaled in said boxes and having winding-drums mounted thereon, the lugs b^3 b^4 , secured to the respective sides and near each end of the car-body, and the adjustable cable or chains connecting said lugs and winding-drums, whereby the car-body may be tilted 50 to discharge the load on either side, substantially as and for the purpose set forth.

6. In a dumping-car, the combination, with the car-body hinged to the bed-frame, as described, of a windlass-shaft having winding-drums mounted thereon and provided with adjustable journal-bearings, the cable or chains D⁴, a worm gear-wheel mounted on said shaft and a worm-shaft engaging with said gear-wheel, whereby the windlass-shaft may be 55 rotated to tilt the car-body, substantially as and for the purpose set forth.
